UNITED STATES PATENT OFFICE.

JULIA BRACKEN WENDT, OF CHICAGO, ILLINOIS.

DESIGN FOR A SPOON, FORK, OR SIMILAR ARTICLE.

No. 39,687.

Specification for Design.

Patented Dec. 15, 1908.

Application filed December 6, 1907. Serial No. 405,453. Term of patent 7 years.

To all whom it may concern:

Be it known that I, JULIA B. WENDT, a citizen of the United States, and residing in Chicago, in the county of Cook and State of Illinois, have invented a new, original, and ornamental Design for Handles for Spoons, Forks, and Similar Articles, of which the following is the specification, reference being had to the accompanying drawings, forming a part thereof.

In the drawings: Figure 1 is a front elevation of a spoon having a handle showing my design. Fig. 2 is a rear elevation of the same.

I claim:

The ornamental design for a handle for a spoon, fork, or similar article as shown.
